ELI W. PHILLIPS, OF BOSTON, MASSACHUSETTS, ASSIGNOR TO AMERICAN TOOL & MACHINE COMPANY, OF BOSTON, MASSACHUSETTS, A CORPORATION OF MASSACHUSETTS.

MEANS FOR MOUNTING AND DRIVING CENTRIFUGAL MACHINES.

1,242,857.

Specification of Letters Patent.

Patented Oct. 9, 1917.

Application filed July 17, 1912. Serial No. 710,087.

To all whom it may concern:

Be it known that I, ELI W. PHILLIPS, citizen of the United States, and resident of Boston, Massachusetts, county of Suffolk, 5 have invented certain new and useful Improvements in Means for Mounting and Driving Centrifugal Machines, of which the following is a specification.

This invention relates to centrifugal machines of the suspended type and is intended to provide simple and effective means for mounting and driving said machines with the minimum amount of vibration and disturbance, while providing a construction 10 and arrangement of bearings for the rotary shaft which can be easily and efficiently lubricated without lubricating the oscillatory bearing on which the machine is suspended. The present construction and arrangement 15 is particularly designed for a direct connected motor drive, and one of the features of the invention consists in so constructing and arranging the parts as to make possible the convenient and rapid dismounting of the 20 machine or disconnecting of the motor for repairs without the necessity of a complete dismemberment or disassembling, that is to say the basket may be removed without disturbing the motor shaft or vice versa, and 25 access may be afforded to the rotary bearings without dismounting the machine or removing the motor.

A further feature of the invention resides in the means whereby there is secured perfect alinement between the motor shaft, the 30 basket shaft and the bearing sleeve, by which it is possible to always assemble the machine with the parts in exactly the relationship that they should sustain to one another. This and other features of the invention will be particularly described herein- 35 after and pointed out in the annexed claims.

In the accompanying drawings is illustrated the preferred embodiment of this invention, in which—

Figure 1 is a side elevation partly in central section showing the relationship of the driving motor connected shaft and other parts of the machine;

Fig. 2 is an enlarged detail elevation of the bearing elements;

Fig. 3 is a cross section on line 3—3 of Fig. 2; and

Fig. 4 is a detail plan view of one of the coupling elements.

55

The socketed hanger *a* is shown firmly bolted to a fixed annular hanger or spacing piece *m* whose upper flanged face is accurately machined to form a circular seat *m'* to receive the base of the motor frame, whose 60 lower periphery is similarly machined to make a perfect fit at *m'* with the spacing piece or upper section *m* of the hanger. For the same reason the top flanged face of the lower hanger section *a* is formed with an 65 annular channel or groove forming a seat for the base or lower end of the hanger section *m*, so that these two parts fit accurately together. The opposed flanges of parts *a* and *m* are bolted securely together, and if 70 the parts are properly machined the middle shaft and the basket shaft must perfectly align with each other and be coaxial with the bearing sleeve *b*. This is an important feature of construction, since I have discovered much of the difficulty encountered 75 in the flexible coupling motor drive has been due to a slight difference in the alinement of the two shafts, and as these types of machines have been heretofore constructed, it 80 is exceedingly difficult, if not impossible, to insure perfect alinement between the motor shaft and the basket shaft.

In practice it is preferred to split the downward extension of the ball sleeve *b* as 85 shown at *b*², and insert therein a tubular bearing *b*³ which is held in place by clamping bolts *b*⁴, which upon being tightened serve to contract the split sleeve tightly upon said bearing sleeve. The bearing cap or 90 head *c*⁶ screws upon the threaded nipple *c*⁷ formed at the upper end of the basket shaft *c* and is held against turning by means of a check bolt *c*⁸ tapped into the upper end of the shaft. This head has also a removable 95 annular centering ring *c*⁹ surrounding and forming a means for accurately centering the flexible coupling members *c*¹⁰. On the fixed supports above the bearing sleeve and the basket shaft is mounted an electric motor 100 the lower end of whose shaft *c*² projects downward in alinement with the basket shaft. An intermediate connecting or extension shaft *c*' is rigidly but detachably secured to the lower end of said motor shaft 105 *c*² by means of a split coupling head *c*⁴ which

is drawn tightly on the motor shaft by fastening bolts, and which terminates at its lower end in a flange c^5 which is secured to a corresponding flange c^5 of the extension shaft c' . This connecting shaft c' extends 5 downward, so that its lower end provided with coupling teeth c^{10} interlocks with corresponding coupling teeth on the upper end of the oscillatory basket shaft c at substantially the level of the center of oscillation of 10 the sleeve. The thrust bearing is also preferably located as closely as practicable to this center of oscillation. The result is a minimum amount of strain on both the coupling and the bearing, and the avoidance 15 of any lateral strain on the coupling.

Below the end of the bearing sleeve there is secured to the basket shaft the rotary hollow oil cup d , provided at its upper end with 20 a hollow flange or rim of larger diameter than its body portion, so that the centrifugal action tends to throw the oil into this enlarged rim d' . Within this rim is located an oil conducting pipe whose open end projects in a direction opposite to the rotation 25 of the oil cup, so that the oil is forced up through the oil pipe d^2 to the oil reservoir d^3 , hence it is delivered by the drip-pipe d^4 mounted in the upper portion of the sleeve 30 b directly upon the flexible coupling or joint, and also upon the thrust bearing. From the thrust bearing the oil flows downward through the vertical groove c^{12} to the bottom of the oil cup. It will be observed that 35 the top of the oil cup is below the ball-bearing part of the sleeve, so that the lubrication of the spherical bearing is avoided, while at the same time a perfect lubrication of the flexible coupling, the thrust bearing and the lateral bearing is obtained. To prevent the 40 undue accumulation of oil above the coupling, I provide an overflow oil duct c^{20} in the middle portion of the sleeve, which serves to lead the oil back into the oil cup. 45 The spiral groove c^{15} forms a lubricating duct for maintaining perfect lubrication around that portion of the shaft forming a lateral bearing and lying within the bushing b^3 . A brake member o is also rigidly secured to the suspended shaft c , and is extended upward so as to have its cylindrical brake surface surround the spherical bearing of the sleeve, the thrust bearing of the shaft and the flexible shaft coupling, so as 55 to reduce to a minimum the strain upon these elements caused by the action of the brake. A clean-out hole for removing sediment from the oil cup is shown at c^{14} , the same being normally plugged by a removable screw plug. The motor shaft immediately below the motor is provided with an oil cup f' from which leads an oil-conducting pipe f^2 which conveys the oil to the reservoir f^3 , by which the bearing of the motor 60 is lubricated.

It will be observed that with the arrangement above described it is possible to completely uncouple the intermediate connecting shaft c' from the motor shaft, and to withdraw it without unshipping the motor or 70 the centrifugal machine, if it is desired to get access to the thrust bearing. On the other hand the brake and the oil cup may be removed without disturbing the upper section of the shaft or the thrust bearing. To 75 remove the basket shaft entirely, its lower section is disconnected at c^{15} , the top cap c^6 is then unscrewed and the shaft c can be dropped through the lower end of the sleeve for removal. As there is usually very scant 80 headroom where these machines are mounted, the sectional arrangement of the shaft makes it very easy to disassemble and reassemble, to a limited extent or completely, without inconvenience. The use of the intermediate connecting shaft c' makes it practicable to locate the flexible joint or coupling at the plane at the center of oscillation, so as to avoid lateral strain, otherwise occasioned by the oscillation of the basket shaft. 85

What I claim is:

1. The combination of a fixed socketed hanger or support, an oscillatory bearing sleeve having a spherical bearing ball intermediate of its upper and lower ends seated 95 in said hanger, thrust bearing carried in said sleeve, a rotary basket-carrying shaft suspended therefrom so as to oscillate with said sleeve, an overhead non-oscillatory motor shaft and coupling members flexibly 100 connecting the upper end of said basket shaft with the downward extension of said motor shaft at substantially the plane of the center of oscillation of said sleeve, and a centralizing buffer surrounding the upper 105 end of said sleeve and opposing a yielding resistance to its oscillation, substantially as described.

2. The combination of a socketed hanger, a ball sleeve seated to oscillate therein, a 110 thrust bearing in said sleeve, a basket-carrying shaft suspended therefrom, an overhead non-oscillatory motor shaft coaxial with said basket shaft, a flexible coupling whose members form an interlocking engagement at 115 substantially the level of the center of oscillation, the upper member being rigidly and detachably secured to the lower end of the motor shaft while the lower coupling member is detachably secured to the upper end 120 of the basket shaft, substantially as described.

3. An oscillatory bearing sleeve for the basket shaft of a centrifugal machine embracing a sleeve member provided with a 125 spherical bearing intermediate of its ends and having an internal ledge, a thrust-bearing supported by said ledge for the suspension of the basket shaft, the lower portion of said sleeve being split and contrac- 130

5 tible, a bushing inserted in the split portion of said sleeve and forming a lateral bearing around said basket shaft and means for contracting said sleeve upon said bushing, substantially as described.

10 4. The combination with the oscillatory ball and sleeve, a thrust bearing mounted therein, a basket-carrying shaft having rigidly secured to its upper end a removable coupling member whose periphery projects 15 beyond the shaft to form a bearing cap, an overhead non-oscillatory motor shaft, a connecting member rigidly and detachably secured to the lower end of said motor shaft and extending downward inside said sleeve 20 to the center of oscillation and provided with interlocking members to form a flexible engagement with the corresponding coupling member of the basket shaft at substantially the plane of the center of oscillation, substantially as described.

25 5. In a centrifugal machine the combination of the oscillating sleeve having a spherical bearing intermediate of its upper and lower ends, a thrust bearing formed inside the sleeve intermediate of its ends, a rotary basket-carrying shaft mounted on said thrust bearing, and an overhead motor shaft coaxial with said basket shaft, and a 30 demountable shaft section detachably secured to the lower end of the motor shaft and extending downwardly into said sleeve and having a flexible coupling connection for driving said basket shaft, substantially 35 as described.

40 6. A motor driven centrifugal embracing in combination a socketed hanger, an oscillatory sleeve centrally mounted therein, thrust bearings and lateral bearings formed in said sleeve, a rotary basket shaft support

ed by said bearings, an overhead driving motor the shaft of which is flexibly connected with said basket shaft, a centralizing supporting frame for supporting the motor and registering shoulders formed respectively 45 upon the motor-supporting frame and the basket shaft hanger concentric with the axis of the motor shaft to secure perfect axial alinement between the motor shaft and the basket shaft, substantially as described. 50

7. A motor driven centrifugal embracing in its construction a motor-supporting frame, a socketed hanger secured thereto, concentric guide rings for securing the proper registering between the motor-support and the hanger, a rotary oscillatory basket shaft suspended centrally inside said hanger, a motor shaft extending downward centrally of the motor frame in alinement with said basket shaft and connected flexibly 60 with said basket shaft by a driving coupling.

8. In a centrifugal machine the combination of an oscillatory rotary basket-supporting shaft suspended at its upper end to permit gyration and rotation, a rigid non-oscillatory rotary driving shaft mounted above said basket shaft and in alinement therewith, the adjacent ends of the said shafts being coupled together at the center of oscillation of the basket shaft by coupling means 70 comprising a series of interlocking oppositely projecting sector-shaped teeth, substantially as described.

In witness whereof, I have subscribed the above specification.

ELI W. PHILLIPS.
